UNITED STATES PATENT OFFICE.

EMIL JAGENBERG, OF DUSSELDORF, GERMANY.

DEVICE FOR FLATTENING FINISHED PAPER BAGS.

1,102,754.

Specification of Letters Patent.

Patented July 7, 1914.

Application filed October 18, 1913. Serial No. 795,835.

To all whom it may concern:

Be it known that I, EMIL JAGENBERG, manufacturer, a subject of the German Emperor, and residing at 107 Himmelgeisterstrasse, Dusseldorf, Germany, have invented certain new and useful Improvements in Devices for Flattening Finished Paper Bags, of which the following is a specification.

10 The present invention relates to an arrangement for folding finished paper bags flat, so that they may be more conveniently packed in piles. Compared to other hitherto known devices of this kind, the present invention is characterized in that the folding plate, after it has settled on the middle of the bag slides toward the bottom end of the bag flattening it more and more, whereupon it finally settles completely at a moderate speed and thereby flattens the bag which with its bottom has in the meantime already entered between the known rollers; eventually the bag passes between two pressure rollers.

25 By the above described operation a smooth folding is insured and all crumpling of the paper bags is avoided as the folding plate settles on the bag more toward the middle than close to the bottom 30 and only then slides toward the bottom, so that the vertical side walls are slightly bulged outward and gradually flattened down progressively toward the bottom. Furthermore the bag is not flattened completely until the bottom has entered between the rollers, which in rolling the bag slightly fold the bottom toward the back, so that the folding plate can fold the bag flat without creasing it.

40 In the accompanying drawing the present invention is exemplified, Figure 1, 2 and 3 being side elevations in three different operative positions; Fig. 4 is a front elevation; and Fig. 5 to 7 show the paper bag 45 before and after it is folded.

On the bed plate α are fitted the two standards b , in which three shafts are journaled parallel to each other. On the lowermost shaft d is fitted between the standards b 50 a roller f , over which a conveyer belt g runs, which is held taut by means of a second roller h , which is rotatably fitted on a shaft h^2 journaled in the standard h^1 . The shaft i , journaled above shaft d carries a roller k 55 between the standards b ; this roller k is slightly rounded on its face and roughened

and is situated above roller f so as to leave only a small gap between them. The third and uppermost shaft m carries an arm n between the standards b , which arm carries at its free end a curved plate q . The shaft d is driven by means of the sprocket c fitted to it or by similar means and a gear wheel p fitted to the shaft d transmits this motion to a gear wheel p^1 on shaft i meshing with it. On shaft i is fitted outside of the standard b a cam r against which a roller s rides, which is rotatably fitted to a rod t by means of a pin s^1 . This rod is hinged at one end by means of a pin y^1 to a lever y fitted to the shaft m ; its other end, which is bifurcated t^1 , fits over the shaft i . A spring u , the ends of which are secured to a standard b and to the lever y respectively, tends to pull down this lever y and therewith also the rod t , so that the roller s is constantly pressed against the cam r . By the shaft i being driven by means of the gears p , p^1 the cam r is rotated and therewith the rod t is vertically reciprocated. In consequence thereof the arm n with the plate q is swung up and down by means of the arm y .

To the plate q is hinged at its lower edge by means of pin x^1 an extension plate or shoe x , which can swing downward and outward but not toward the shaft m , as in this direction its movement is limited by a stop z fitted to it and adapted to abut against the plate q . A spring j the ends of which are secured to the plate q and the plate x by aid of brackets j^1 tends to hold up this plate x .

Behind the rollers f and k a further pair of rollers e is journaled between the standards and close above each other. This pair of rollers is preferably driven at a somewhat greater angular velocity than the rollers f and k by the gears p , p^1 .

55 Behind the rollers f and k a further pair of rollers e is journaled between the standards and close above each other. This pair of rollers is preferably driven at a somewhat greater angular velocity than the rollers f and k by the gears p , p^1 . To the plate x are rotatably fitted at its front edge rollers c , which, on the arm n being lowered, meet the cams l provided on the insides of the standards b .

The paper bags to be folded are placed behind each other on the belt conveyer g , which advances the first bag toward the roller k . Then the arm n moves down so that plate x settles from above about on the middle of the bag and presses down the same, so that the sides of the bag are bulged outward. The plate x gradually approaches the bottom of the bag and therewith also the belt g . In consequence

thereof the bag is flattened more and more until the arm *n* has reached the position shown in Fig. 2 in which the rollers *c* meet the cams *l*. The bag has now been folded 5 in the manner shown in Fig. 6. The front end *v*¹ of the inclined bottom has then already entered between the rollers *f* and *k* which now draw the bag between them and completely fold down the bottom. At the 10 same time the lever *n* turns farther so that the plate *x* is pressed down by the rollers *c* riding on the cams *l* and is pushed into the gap between the rollers *f* and *k*. (Fig. 3). The bag is thus completely flattened by 15 passing between the rollers *f* and *k* and by the simultaneous downward pressure of the plate *x* while the latter is advanced at a slow rate. The rounded form of the face of the roller *k*, Fig. 4, prevents the bag 20 being crumpled as there is therefore no pressure between the rollers *k* and *f*, but only between the rollers *c*, where the bag is already flattened. The air pressed out during the flattening operation can thus escape 25 at the corners *w* and thence along the edges of the folds to the mouth of the bag so that no air is entrapped which might during the flattening operation inflate the corners *w* and prevent their being smoothly flattened. 30 The rollers *c*, between which the bag is now fed, draw it between themselves and thereby compress it in such a manner, that it retains the flattened shape.

The cam *r* is of such a shape that the 35 plate *q* is moved downward in correspondence with the advance of the belt *g*, whereupon it returns rapidly so that it will not prevent the bag from completely passing between the rollers.

The rollers *c* and the cams *l* may also be 40 omitted, so that then the front edge of the

plate *x* abuts against the roller *k* and slides down along the same. This arrangement is, however, less advantageous, as the plate *x* might then easily pull back the bag with it on its return stroke.

I claim:

1. A machine of the character described, comprising a standard, a pair of folding rollers journaled therein and adapted to engage a paper bag, one of said rollers having a slightly rounded face, an oscillative plate pivoted to the standard, a shoe pivoted to said plate, a cam that is adapted to operatively engage the shoe and press the same against the bag bottom, and a pair of pressure rollers arranged back of the folding rollers.

2. Device for flattening finished paper bags, boxes, and the like, comprising a belt 60 conveyer adapted to convey the bag between two flattening rollers, and a flattening slide, the said flattening slide adapted to rock and settle down about the middle of the bag, and to compress the bag partly while sliding toward its bottom in consequence of its 65 rocking motion and feed it between the said rollers, the upper one of said rollers having a slightly rounded face, means for pressing down the slide completely on the conveyer belt and advancing it into the gap between the said rollers, behind the first said pair of rollers a second pair of pressing rollers 70 for the flattened bags.

In testimony whereof I have hereunto set 75 my signature in the presence of two witnesses.

EMIL JAGENBERG.
